UNITED STATES PATENT OFFICE

HENRY C. MILLER, OF WATERFORD, NEW YORK

CENTRALIZING MECHANISM FOR SEWING MACHINES

Application filed July 26, 1922. Serial No. 577,714.

My invention relates to improvements in sewing machines, particularly to what is known in the art as a "centralizer", designed to accurately form a central buttonhole in a 5 collar, or other article.

In order to accurately deliver and locate a collar to the stitching mechanism by a mechanical locating means, the mechanism must be simple, efficient, durable and arranged so 10 that an operator can conveniently manipulate it and adjust the parts. Furthermore the mechanism must be of such a nature that it cannot under any circumstances injure the work by the placing of too much strain there- 15 on, and for practical purposes it must be so arranged that with little training and experience an operator can produce first class work, and materially increase the output over the present methods employed.

20 An object of the present invention is the provision of means for conveniently and quickly centralizing and gauging a collar, then automatically gripping the collar, and automatically releasing the centralizing means from the collar and transferring the gripped and gauged collar to the buttonhole stitching machine, with the ends of the collar free or flexed, so that when it contacts with the machine head it will not displace the 25 gripped part of the collar when placed under the cloth clamp.

Another object of the invention is to provide improved means for engaging a collar when centralizing it, and releasing the collar 30 when delivering it to the buttonhole machine.

A further object of the invention is to provide means for automatically starting the various mechanisms when a locator or charger is advanced with a collar to the buttonhole machine, and cooperating means for removing the grip of the charger from the collar, and removing the charger from the path of movement of the cloth clamp.

45 A still further object of the invention is to provide means actuated by the charger for positioning a collar to receive a central button hole, and automatically operating power control mechanism to set into motion the stitch forming mechanism and associated mechanism in a buttonhole machine, includ-

ing control of the cloth clamp, control of the cutting blade and stop motion means, whereby an operator has only to centralize a collar and move it by the charger, and in so doing start the buttonhole machine which 55 upon completion of its cycle of movement is automatically stopped, the power control mechanism in the meantime having been automatically thrown out of operative position and is ready for the next succeeding operation. 60

A further object of the invention is to provide improvements in the power control and actuating mechanism, same being constructed and arranged to be tripped when a collar is positioned to receive a buttonhole, or to 65 be manually tripped for restitching and repairing a buttonhole which has been improperly formed.

As a whole the objects of the invention are to provide improved means for centralizing a collar; to provide a locator or charger for automatically gripping and gauging the centralized collar; to provide manual means for conveniently operating the charger to introduce the gripped and gauged collar to a buttonhole machine; to provide means actuated by the charger for automatically releasing a collar from the centralizer; to provide means actuated by the charger for operating a power control mechanism; to provide means actuated by the power control mechanism to automatically lower the cloth clamp, kick the charger from the path of movement of the cloth clamp, and subsequently start the buttonhole machine; and to provide means for operating the power control mechanism either by the charger, or at the will of the operator. 85

The invention also comprehends improvements in the details of construction and arrangement of parts which will be hereinafter described and particularly pointed out in the claims.

In the drawings:

Figure 1 is a perspective view of my improved mechanism as applied to a Singer buttonhole machine, the latter being conventionally shown.

Figure 16 is a detail perspective view of the dog employed in the power control.

In the drawings, 1 indicates a frame provided with a support 2, on which is mounted a buttonhole machine of the well known Singer square bar or purl stitch type with certain of my improvements applied thereto and which will be hereinafter specifically referred to. In applying my improvements to this type of machine, the collar to be operated upon is centered lengthwise to, or parallel with the head, due to the fact that the buttonhole is formed longitudinally of the head, therefore a collar receiving table 3 is

shown as extending outwardly from one end of the machine and at right angle to the head as shown in Fig. 1.

Depending from the front of the support 2, is a casting 4, provided with end bearings 5 and two intermediate bearings 6—6. In each end bearing 5 is a sleeve 6^a, and on the inner end thereof is fastened a mutilated pinion 7, and on the outer end of the sleeve is a centering arm 8. Mounted on studs 9 in the intermediate bearings 6, are mutilated gears 10, which mesh with the mutilated pinions 7. Each centering arm 8, is provided with an offset 11, formed with an opening 12, and in alignment with the opening is a bore 13, formed in the free end or head of said arm. Extending thru the bore and the opening is a rod 14, pivoted at its lower end to a bell crank lever 15, which in turn is pivoted to an ear extending from the arm below the offset portion 11. On the rod 14 between the offset portion 11, and a collar 16, is mounted a spring 17, the tension of which normally projects the end 18, of the rod beyond the free end of the head. The lower end of the bell crank lever 15, is disposed adjacent the sleeve 6^a, to be engaged by a pin 19, mounted in said sleeve and normally projecting beyond the rear end of same. The rear ends of the pins 19, are engaged by arms 20, supported on a shaft 21, mounted in bearings on the casting 4, one end of the shaft being cranked as at 22, and at said cranked end it is provided with a lever 23.

To normally spread the free ends of the centering arms 8, a spring 24 is attached at one end to one of the mutilated pinions 7, and is attached at its opposite end to a pin on the casting 4, and to remove the shock incident to the action of the spring, and thereby cushion the movement when a collar is released from the ends 18, of the rods, I provide chains 25, attached at their outer ends to the arms and their inner ends secured to an intermediate spring 26.

Mounted on the top rear corner of the support 2, is a standard 27, provided with aligned bearings to receive a shaft 28. On the shaft is fixed a tiltable frame 29, formed on one side with a guideway 30, and on its opposite side with aligned bearings 31, a spring 30^a being employed to hold the frame in operative relation. Slidably mounted in the aligned bearings 31, is a rod 32, provided on its rear end beyond the frame 29, with an adjustable collar 33, and at its forward end it is extended beyond the frame and is slightly bent upwardly and then at right angle as at 34, to lie over the table 3. Clamped on the right angle portion 34, at 35, is a stem 36, and on the rear end of same is freely mounted a gripper 37, which is normally elevated above the table 3. The gripper comprises a head and a pair of downwardly curved arms 37^a, serrated on their rear lower edges.

as at 38, and extending across the two arms near the head is a bar 39, having pins 40, to which are fastened the ends of a spring 40^a, which passes around a sleeve 40^b, extending from the head. Extending thru the bar 39, close to the arms 37^a, are light rods 41 which extend rearwardly and the ends are turned downwardly as at 41^a, adjacent the serrated portions 38, said ends 41^a projecting below the bottoms of the arms to form gauges.

42 indicates a trigger slidably mounted under the frame 29. This trigger is provided with a slot 42^a, thru which passes a holding screw 43, and in advance of the slot and screw is an opening 44, adapted to register with a recess 45 in the bottom of the frame 29. The rear end of the trigger 42, is turned upwardly and is formed with an opening 46 thru which the rod 32 passes. The trigger is retracted toward the rear by a spring 47, secured at one end to the screw 43, and its opposite end is fastened to a pin 48, depending from the bar. Projecting upwardly from the support 2, and disposed in alignment with the recess 45, is a pin 45^a, which at the proper time cooperates with the opening 44 and recess 45 but normally the trigger rides over the upper end of the pin to hold the frame 29 elevated, as shown in Figure 5. To relieve the shock, and cushion the parts when operated, leather or the like washers 49 are placed on the rod 32 between the upturned end of the trigger, the frame, and the collar 33.

Extending laterally from the bar 32, and guided in the guideway 30, of the frame 29, is a trip 50, the outer end of which is positioned in the path of the lever 23 to actuate the depending arms 20 on the shaft 21, when delivering a collar to the buttonhole machine.

51, indicates a link angularly bent at its front end and formed with an opening 52 thru which extends the rod 32, and on the rod is mounted an adjustable collar 54^a, to cooperate with the angular bent end of the link in the operation of the machine.

The rear end of the link 51, is pivoted to an arm 53 of a crank lever 54, pivoted at 55, to the standard 27, and pivoted to another arm 56, of said lever is a link 57 which extends thru a pin 58, mounted in a lever 59, secured on a shaft 60. The link 57 projects some distance beyond the pin 58, and is provided with a spring 61, held normally in adjusted position below the pin 58 by a collar 62.

On one end of the shaft 60, is an arm 63, to which is pivoted a lever 64 provided on its end with a roller 64^a, the lever being held in operative position by a pin 65 and a spring 66. The roller 64^a is positioned so that in one movement of the shaft 60, it (the roller) will contact with an adjustable cam 67 secured on the crank arm 68, of the shaft 28, to upwardly tilt the frame 29 on its axis to release the collar.

Secured on the shaft 60, is a lever 70, to control the starting mechanism of the buttonhole machine. Pivoted to lever 70, is a rod 71, which extends thru a pin 72 pivoted in a lever 73, fixed to a clamp raising and starter shaft 74. The rod extends beyond the pin and is provided with a collar 75, and on the rod between the pin 72 and an adjustable collar 76 is a spring 77. On the shaft 74 is an arm 78 with a roller 79, to engage the end of the clamp 79^a, and cooperating with the starting and stopping mechanism is a latch 80, mounted on a shaft 81 having means to be operated and controlled by said stopping and starting mechanism. This mechanism is shown and described in my Patent No. 1,457,742, dated June 5, 1923, in view of which it is not deemed necessary to illustrate it further than the diagrammatic illustration shown in the drawing.

Bolted in the lower part of frame 1, is a stud 83, provided at its inner end with a reduced portion 84. Rotatably mounted on the stud is a power driven wheel 85, and on the hub 86, of the latter is mounted a grooved trigger wheel 87. On one of the spokes of the power driven wheel is pivoted a dog 88, having a depending lug 89, which engages in a recess 90 formed in one of the spokes of the grooved trigger wheel 87. A pair of springs 91 connect the power driven wheel and the grooved trigger wheel and cause one wall 92 of the recess 90, to impinge the lug 89 to normally rock the dog on its pivot and hold its end in an elevated position, as shown in Fig. 14. The springs serve to bring the trigger wheel up against a stop 87^a, and therefore cause the two wheels to normally rotate together. On the reduced portion 84, of the stud shaft is a bushing, and on this bushing is freely mounted a toothed wheel 93, held in position by a washer and a screw 94. Pivoted to the toothed wheel is a pitman 95, the end of which is formed into a piston 96, provided with a vent opening 97 and a valve seat 98, which receives a valve 99. The piston reciprocates in a cylinder 100 which is pivoted on a pin 101, extending from a lever 102 mounted on the shaft 60. The cylinder is provided with an opening 103 having a valve 104 to regulate the descent of the piston, the piston and cylinder forming a dash pot to cushion the shock of the parts, as will appear later on in the description of the operation.

The lever 102, is located adjacent lever 59, and is provided about midway its length with a stud 104^a, on which is supported a substantially curved link 105, and to this link is attached one end of a spring 106, the lower end being secured at 107 to a bar on the frame 1.

To control the power from the power driven wheel, a belt 108 loosely lies in the groove of wheel 87, and is attached at one

end to an adjustable support 109, secured to frame 1. To the opposite end of the belt is secured a compensating spring 110, and to the opposite end of the spring is attached a rod 111. The rod extends thru an opening formed in a lug 112 on an arm 113 of the crank lever 54, and is provided with an adjustable collar 115, with which the lug cooperates, while the upper free end of the rod 111 is formed into a finger grip which is arranged in convenient reach of the operator.

The foregoing description discloses the application of the invention to a buttonhole machine of the Singer type, which because of the way in which the buttonhole is formed necessitates a charger and means to release the ends of a collar, but the improvement is not to be construed as being applicable to this type of machine alone, and therefore in Figures 10 to 13, I have illustrated the invention as applied to a Reece buttonhole machine. Because of the fact that in machines of this type the buttonholes are made cross-wise of the head it is essential that the invention be somewhat modified to meet the conditions.

120 indicates conventionally a part of a Reece buttonhole machine wherein the head and stitching mechanism move bodily in the formation of a buttonhole. Mounted to swing on trunnions 121 under the support for the machine, is a frame 122, provided at opposite ends with bearings 123, similar to bearings 5 in the preferred form of the invention, and provided with mutilated pinions and gears 124, and rods 125, a spring 126 being employed to retain the gears and associated parts in normal relation. On the frame 122, is mounted a shaft 127, from which depend arms 128 to engage and actuate the rods 125 in one direction, and extending upwardly from the shaft is an extension 129. Associated with each bearing 123, is a centering arm 130, which receives a rod 131, connected with a crank lever 132 arranged in cooperative relation with the rod 125, the rod having parts similar to those previously described.

Depending from the frame 122, is a lug 134, provided with a slot 135 thru which extends a threaded rod 136, which is swivelled to the machine frame 137, and on the rod is a nut 138 to limit the movement of the swinging frame 122 in one direction. Extending from the swinging frame is a lever 139, which contacts with a lever 140, pivoted at 141 to the buttonhole machine base, the upper end of this lever being positioned to strike the trigger 142, to start the buttonhole machine.

Swivelled under the base of the machine is a lever 143, a flexible connection or chain 144 connecting one end of the lever to the lower frame of the sewing mechanism indicated at 145. The opposite end of the lever 143 is disposed adjacent the end of the ex-

tension 129, so that when the sewing mechanism operates and exerts a pull on the chain, the lever 143 will be rocked, and thru extension 129, the shaft 127 will be rocked and withdraw the rods 131 in the arms 130.

From the right hand side of the swinging frame 122, extends a handle 146, by means of which, in this form of the invention, the centralized collar is delivered to the button-hole machine.

I will now describe the operation of the improvement as shown applied to the Singer buttonhole machine shown in Figures 1 to 9. Assume the parts are in the position shown in Figure 1, that is the centering arms 8, are spread apart by the spring 24 and the mutilated pinions and gears 7 and 10, said arms being held in this position by the flexible connection 25-26. The operator now takes a collar which has previously been buttonholed at its ends by another buttonhole forming machine, and draws in the centering arms slightly toward each other and slips the end buttonholes over the ends 18 of the rods 14, and then releases the arms, which because of the action of the spring 24 and the gears are equally drawn apart and stretch the collar and accurately centralize it over the table 3. Obviously any length of collar can be centered, as it is evident that the centralizing arms will in every instance move toward and from each other at the same speed and the same distance, and when a collar is engaged by the ends 18, the movement of the arms is limited by the length of the collar.

The center of the collar having been accurately located to be presented to the buttonhole machine, the charger rod 32 is grasped by the operator and moved forwardly until the stop collar 33 contacts with the upturned end of the trigger 42, and advances the latter against the tension of spring 47 until the opening 44 aligns with the pin 45^a and the recess 45, whereupon the front end of the charger frame is tilted downwardly by the spring 30^a. This movement lowers the grippers 37, and the serrated edges 38 engage the collar, indicated at b, and then the operator moves the charger towards the buttonhole machine, and in so doing the projecting end 50^a of the trip pin 50, contacts with the upper end of the lever 23 and thereby rocks the shaft 21, which movement causes the ends of arms 20 to force the rods 19, toward the front of the frame. The rods engage and rock the crank levers 15, which retract the ends 18 of the rods 14 from the end buttonholes of the collar and within the bores of the arms, and against the tension of springs 17. This action is timed so as to release the ends of the collar before it reaches locating position under the cloth clamp to receive the center buttonhole, so as to leave the ends of said collar free or flexed. The

movement of the charger is continued until the collar reaches its properly located position under the cloth clamp, at which time the collar 54^a contacts with the inturned end 5 of the link 51, and thru its connections with arm 53 of the crank lever 54, rocks the latter, and thereby an upward pull is imparted to the trigger rod 111, movement of the crank lever correspondingly pulls up the link 57 to 10 position the spring 61 for a future operation. The pull on the trigger 111 causes the belt 108 to frictionally engage the trigger wheel 87, which causes said wheel to resist the pull of return springs 91 against the power driven 15 wheel 85. This action retards the movement of the trigger wheel with reference to the power driven wheel and therefore the wall 92^a of the recess 90 engages the lug 89 and swings the dog 88 on its pivot, and its free 20 end is brought into engagement with a tooth of the toothed wheel 93. The engagement of the dog with the tooth wheel transmits rotary motion to the tooth wheel, and thru the pitman 95 and cylinder 100 and its connection 25 with the lever 102, rocks the latter upwardly and correspondingly rocks the shaft 60. This rocking of the shaft raises the rod 71 and thru the lever 73 the lever 78 is raised and the cloth clamp which is spring actuated 30 is first lowered to hold the collar, and upon further movement of rod 71 the connections controlled from shaft 74 and not specifically illustrated start the buttonhole machine.

Between the time the cloth clamp is lowered, and the buttonhole machine is started, the parts are so timed that rocking the shaft 60 will cause the latch lever 64 to contact with the cam 67, on rod 68 and rock the charger on its axis and elevate the gripper 40 from the collar, and immediately thereafter, through the reversal of the movement of the crank lever 54, by lever 59 contacting with spring 61 and pulling on the connection 57, link 51 engages the collar 54^a on rod 32 and 45 kicks the charger from the path of movement of the cloth clamp. As soon as the charger is tilted upwardly on its axis, the spring 47 acts to return the trigger 42 to its normal position, as shown in Fig. 5.

50 In order to provide for proper timing and accuracy of movement, and to compensate for any irregularity in movement, I provide the springs 61 and 77, so that in case there is a slight variation in the action the springs 55 will take it up and prevent breakage. In addition to accomplishing these functions, rocking of shaft 60, exerts a pull on spring 106, and places it under tension to subsequently return the power control parts to 60 normal position.

Operation of the lever 73 actuates the starting mechanism which in turn rocks the shaft 81, and positions the latch 80, over the lug 80^a, and prevents actuation of the shaft 74 65 until the complete cycle of operation of the

buttonhole machine is completed. If the stitches are properly formed, the stop motion mechanism will engage the stud 80^b on the lever 80^c and rock the shaft 81, and disengage the latch 80 from the lug 80^a and the shaft 74, will permit operation of the cutting blade, and the cloth clamp will be elevated as a part of the cycle of operation of the button-hole machine. If however the stitches are improperly formed, and the stop motion fails to come back to normal position, the latch remains over the lug and neither the cutting blade or cloth clamp will be actuated, and the collar will therefore be held in located position.

To be assured that the collar is properly gauged as to the distance the buttonhole should be from the edge, the gauges 41^a are provided. These gauges are at all times in contact with the table 3, irrespective of the position of the gripper, the very light spring 40^a being employed to maintain this relationship. Consequently when the charger is moved toward a centralized collar, the gauges will contact with it and properly position it prior to the time the gripper is lowered. When the cloth clamp engages the collar and the gripper is elevated and kicked back, the gauges drag over the edge and surface of the collar, and automatically assume position to be moved back to gauge the next succeeding centralized collar, while the clamped collar is receiving the buttonhole. When the charger is released and automatically kicked back from the positioned collar, it is pushed back only a short distance out of the path of movement of the cloth clamp, but not far enough back to grip the next collar. The operator may however proceed to place the next collar on the ends 18 of the rods 14 to centralize the next collar, so that when the charger is manually drawn back, the next collar can be gauged and gripped and ready to be delivered to the buttonhole machine, as previously described.

In the return movement of the charger for gripping the next collar, the end 50^x of the trip 50 strikes the angularly disposed end of the lever 23, and flexes it outwardly, and permits said end 50^x of the trip to pass and position itself on the opposite side of the lever to effect the release of the collar in the next operation.

When the buttonhole machine is started, the spring 106 immediately commences to exert its tension, and to relieve the strain on the latch 80 and lug 80^a and its cooperating parts on the buttonhole machine, the link 105 is provided. The link is so formed and positioned that when the lever 102 is moved upwardly, it draws said spring toward the shaft 60 and close to the vertical alignment between the point of attachment 107 and the shaft, so that the line of pull, or the tension of the

spring is almost over the center of said shaft 60 as shown in Figure 3^c.

As the ends of the collar are released from the centralizer prior to being delivered to the buttonhole machine, and when it is held by the cloth clamp during the period the stitch forming operation is performed, the ends are free, consequently if the cloth contacts with the head of the machine it will in no way affect or displace the collar while being operated upon.

When tripping the power control to bring it into operation as previously described the toothed wheel 93 makes a complete rotation without stopping, the dog 88 however only engages the tooth for one half the revolution of the wheel and then automatically becomes disengaged, and during the other half of the revolution, the parts move by gravity until the pitman 95 reaches its lowermost position. This is made possible by the construction and arrangement of the pitman and the cylinder connection. That is, to say, after the piston reaches its highest position, the vents in the dash pot arrangement permit a comparatively free downward movement of the piston, and when the cylinder and its connections drop, the shock is cushioned. In other words, in the operating of the power control, that is when the trigger belt 108 has been pulled, it causes the dog to contact with any tooth nearest it which creates labor between the dog and the engaged tooth, hence the tooth and dog will not separate, and to this extent, even if pull on the belt should be removed in the first half of the revolution of the toothed wheel, the interlock would continue for the half stroke. Then immediately the pitman connection reaches the highest point in the rotation of the wheel, that is one half revolution, the labor on the piston is relieved and the springs 91, come into play and return the trigger wheel to its normal position with respect to the power wheel, and in consequence of this movement the wall 92 of the recess 90, contacts with the lug 89 and disengages the dog from the tooth, and the pitman falls by gravity but the cylinder and its connected parts remain elevated until the cycle of movement of the buttonhole machine is completed.

To illustrate the operation of the connections between the actuated parts and the power control mechanism reference is made to the showing in Figs. 2, 3 and 3^b. In this figure the dotted position of levers 59, 70 and 73 indicate the location of the levers in their movement by the power control when same was operated by either link 51 or rod 111. Until said levers reach the dotted positions the motion of lever 59 is idle, but the movement of lever 70 to dotted position raises lever 73, far enough to lift the arm 78 from the tail of the cloth clamp and thereby the cloth clamp in this interval is lowered

on the collar. Then upon further continued movement of the pitman and cylinder connection the levers 59, 70 and 73 are farther moved and in this movement the lever 59, acting on the spring 61, pulls on rod 57, and kicks the charger away from the clamp, and the levers 70 and 73 impart a further rocking movement to shaft 74 to start the buttonhole machine. Upon the starting of the buttonhole machine, the latch 80 is automatically located in latching position over arm 80^a, where it remains during the entire buttonhole making cycle, as generally described in my aforesaid patent. The parts however are so proportioned and timed that the lever 70 will accomplish its function of first lowering the cloth clamp, and immediately thereafter the lever 59 will act to kick out the charger, and following this action the sewing machine will be started. The result is that the action of the power consecutively lowers the cloth clamp elevates and kicks the charger out of the path of movement of the cloth clamp, and starts the buttonhole machine. After these actions have been accomplished the levers 59 and 70, and 73 drop back slightly and are held in this position by the latch 80 while the cycle of movement of the buttonhole machine is being completed, but of course in the meantime the pitman 95 is returned to its normal position, while the cylinder 100 remains suspended.

Going back to the position of the parts while making and stitching a buttonhole, and assuming the operation is completed, and the buttonhole has been properly formed, the stop motion mechanism latch (not shown) actuates the lever 80^a and rocks the shaft 81 and throws the latch 80 from over the lug 80^a and permits shaft 74 to be rocked, which permits the cutting blade to operate, and subsequently the lever 78 acts on the cloth clamp to elevate it and release the collar.

When the shaft 60 is reversely rocked the spring 106 pulls down the latch lever 64, and as the same is pivoted to lever 63, it passes by the cam 67 to become positioned for the next operation. Reversal of the movement of the shaft 60, also raises the lever 59, on the rod 57 but without imparting any movement to the latter, as said rod was returned to its normal position at the time the charger was kicked from under the cloth clamp.

During the time the power control mechanism parts are returning to normal position and to relieve the shock and diminish the noise, the dash pot arrangement comes into play. As the lever 102, lowers, the cylinder is correspondingly lowered, but because of the check valve 98 in the piston, and regulation of the egress of air thru bent opening 103 obviously, the descent of the cylinder is retarded and the consequent cushion removes all possibility of shock on the moving parts.

If the stop motion fails to be returned accurately to its exact normal position, then the projection 80^b on lever 80^c will not be engaged to operate the latch 80, with the result that while the stitching mechanism will have completed its cycle of movement, the lever 80^c cannot be rocked, hence the cloth clamp will not be elevated, nor will the cutting blade be operated, the cutting blade and cloth clamp being controlled by a defect in the thread, this mechanism being shown and described in my Patent No. 1,457,742. It is, however, not deemed necessary to illustrate this mechanism, although it is evident it is important that mention of it be made to show that the power control mechanism may be used with such an arrangement.

After the buttonhole machine has completed its operation and is stopped, and if per chance the stitches are improperly formed, levers 59, 70 and 73, will remain in position shown by dotted lines in Fig. 2, consequently the cloth clamp will continue to hold the collar in clamped relation. The operator now cures the defect in the thread and to re-stitch the same buttonhole, the operator pulls upon the rod 111 which again throws into operation the power control mechanism, and the stitching mechanism is again started to make another complete cycle. It is to be noted however that when re-stitching a buttonhole the movement of the cylinder 100, is not as great as when first starting the mechanism inasmuch as the various levers are held suspended by the latch 80, although the stroke of the piston 95 is always the same.

In addition to the cloth clamp and starter shaft 74 carrying the cloth clamp lifting lever 78, it may also be provided with thread control locking means such as shown in my Patent No. 1,438,848 issued December 12, 1922 (but not herein illustrated) which if the thread breaks or plays out in either the needle or bobbin, it prevents the cutting of the buttonhole and prevents automatic raising of the cloth clamp until the stitches are properly mended. If this occurs, obviously the latch and associated parts will remain in suspended position and it is only necessary to replace the played out or broken thread, and then raise the rod 111 to re-start the stitching operation and mend the buttonhole, which if properly done, releases the collar, the power control having in the meantime been automatically disconnected.

It is evident that when the ends 18 of the rods 14 are released from the end buttonholes, and the centralizing arms assume their normal position, the elastic shock absorber 25 will absorb and cushion the blow and act as a stop. It will of course be understood this detail may be changed to provide other forms of cushioned stops. Furthermore it will be understood that the centralizer may

be manually pulled in both directions if desired, but I prefer the arrangement shown and described.

As previously stated, Figs. 1 to 9 represent the application of the invention to the Singer type of buttonhole machine, and to apply the power control, and at the same time prevent raising the cloth clamp and operation of the cutting blade, I must provide the automatic latch to utilize the centralizing means, but when using the latter means I must use a charger as the buttonhole is made lengthwise of the machine.

In applying the invention to a machine, wherein the stitching mechanism is bodily moved in the formation of a buttonhole, such for instance as the Reece type, shown in Figures 10 to 13, or other machines making buttonholes crosswise of the arm, different conditions from those described must be met, and therefore the arrangement of the parts forming the improvements must correspondingly be made to meet the conditions.

In the form of the invention disclosed in Figures 10 to 13 the whole centralizing mechanism swings on the trunnions 121 when centering a collar. The operator places the collar on the projecting ends 131 of the rods of the normally forwardly inclined arms 130 in the same manner heretofore described, and then pushes on the handle 146 and swings the centralizing arms with the stretched collar attached, toward the buttonhole machine. In doing this the lever 139 strikes the swivelled lever 140, and the latter contacts with the trigger 142 and starts the buttonhole machine. The inward movement of the centralizer is limited by the lug 134, contacting with the stop 138 on the stem 136, at which time the collar is properly located to receive the center buttonhole. Starting of the buttonhole machine automatically operates the cloth clamp to engage the collar as is customary in machines of this type, and then the moving arm and stitching mechanism, including the arm 145 are automatically put into operation, which pulls on the flexible member 144 and rocks the swivelled lever 143 and its opposite end engages the extension 129. Movement of the extension 129, rocks the shaft 127, and the arms 128 act on the rods 125 to withdraw the rods 131 and thereby the collar is released.

Figure 13 illustrates an end view of the form of centralizing mechanism used on the Reece type of machine, the full lines representing the position of the parts when the collar is introduced to the buttonhole machine, and the latter is started, and the dotted lines indicating the position of the parts when in normal position to receive another collar to be operated upon.

In the Reece machine the trigger 142 is operated which throws on the power to first operate the cutting blade of the buttonhole

machine, and then the power is automatically thrown to the stitching mechanism. After the stitching is completed, the parts are thrown to normal position and the cloth clamp is automatically elevated to release the collar. Therefore, when my improved centralizer is applied to this type of machine, all the operator has to do is to move the centralizer with a collar thereon toward the buttonhole machine, and by means such as described the trigger 142 is operated, thus simplifying the motions of the operator when making buttonholes.

In the centralizer mechanism for either type of machine the collar engaging rods are withdrawn at any position of the arms, no matter what size collar may be operated on, the operator having to pay no attention as to the sizes and variations thereof. The whole cycle of operation is performed and the centralizing movement in stretching a collar is entirely independent of the operator in so far as starting the machine is concerned, this being due to the fact that the springs are arranged to spread the centralizing arms as the collar is placed in position on the rods. This is true irrespective of whether or not large or small size collars are being located.

What I claim is:

1. A centralizer, comprising a pair of swinging arms free at their ends to engage an article to be centered, and means operating on the arms at their pivotal points and free of other connection with the arms to cause said arms to swing in unison.

2. A centralizer, comprising a pair of swinging arms free at their ends to swing in an arc and to engage an article to be centered, and means including a series of rotatably mounted elements for operating the arms to cause them to swing an equal distance to and from a predetermined center.

3. A centralizer, comprising a pair of swinging arms of exactly equal length from their axis, means carried by the arms to engage and stretch an article to be centered, rotating means connecting the arms to cause them to swing an equal distance to and from a predetermined center.

4. A centralizer, comprising a pair of swinging arms free at their ends, gauging pins at the free ends of the swinging arms and operating in line therewith to engage an article to be centered, and means connecting the arms to cause them to swing in unison.

5. A centralizer, comprising a pair of swinging arms free at their ends, gauges on the free ends of the arms to engage an article to be centered, means connecting the arms to cause them to swing in unison, and means for releasing the centered article in any position of the arms.

6. A centralizer, comprising a pair of swinging arms of exactly the same length and free at their ends, gauges at the free

ends of the arms to center an article, means for causing the arms to move the same distance toward and from each other, and means for releasing the centered article in any position of the arms.

7. A centralizer, comprising two arms pivoted at their lower ends, gauges at the free ends of the two arms, means connecting the two arms to cause their upper free ends to swing toward and from a predetermined center, and means for releasing a centered and gauged article in any position of the swinging arms.

8. A centralizer, comprising two arms connected together to swing the same distance toward and from each other, hollow shafts on which the arms are mounted, gauges at the free ends of the arms, and means in the hollow shafts for projecting or withdrawing the gauges in any position of the swinging arms.

9. A collar centralizer for buttonhole stitching machines, comprising two swinging arms to which the ends of the collar are removably secured, rotating means connecting the arms to cause them to swing in unison from each other when centering a collar, and manual means for swinging the arms toward each other.

10. A centralizer, comprising two moving elements adapted to move an equal distance toward and from each other and having gauges to engage an article to be centered, means for releasing the gauges from the article, and means engaging the centered article and delivering it to mechanism where it is to be operated upon and in this movement actuating the means for releasing the gauges from the article.

11. A centralizer, comprising two moving elements adapted to move an equal distance toward and from each other and having gauges to engage an article to be centered, means for engaging the centered article and delivering it to mechanism where it is to be operated upon, and automatic means for releasing the gauges from the article.

12. A centralizer, comprising two moving elements interconnected through rotating members to cause said elements to move an equal distance toward and from each other and carrying end gauges, means to cause the two elements and gauges to move equal distances toward and from each other irrespective of the length of the article being centered, automatic means to cause the two elements to gauge and center the article, and means for holding the gauged article at its center to advance it to a machine to be operated upon.

13. In combination, a buttonhole machine, two elements adapted to be moved toward and from each other and located each side of and beyond the stitching point of the buttonhole machine, gauges on the elements to

engage the end buttonholes in a collar, means for presenting the centered collar to the buttonhole machine to receive the center buttonhole, and means for automatically releasing the gauges from the collar before completion of the center buttonhole.

14. In combination, a buttonhole machine, a centralizer to center a collar in advance of the buttonhole machine, means for conveying the centered collar to the buttonhole machine, and means actuated by the conveying means when introducing a collar to the buttonhole machine to start the latter.

15. In combination, a buttonhole machine, a centralizer to center a collar in advance of the buttonhole machine, means for conveying the centered collar to the buttonhole machine, means actuated by the conveying means when introducing a collar to the buttonhole machine to start the latter, and means for automatically releasing the collar from the centralizing means.

16. In combination, a buttonhole machine, a centralizer to center a collar in advance of the buttonhole machine, means for conveying the centered collar to the buttonhole machine, means actuated by the conveying means when introducing a collar to the buttonhole machine to start the latter, and means actuated by movement of the conveying means to automatically release the collar from the centralizing means.

17. In combination, a buttonhole machine including automatic cloth clamp operating means, automatic starting mechanism, means engaging the ends of an article to locate same with reference to the buttonhole machine including two elements movable equal distances toward and from each other simultaneously, manually operated means for subsequent automatic gripping of the located article and to thereafter introduce the article to the buttonhole machine and automatically release the ends of the article and lower the cloth clamp and release the conveying means from the article after the cloth clamp has automatically clamped the article, and actuate the starting mechanism.

18. In combination, a buttonhole machine including automatic cloth clamp operating means, and starting mechanism, a centralizer including elements movable simultaneously and equi-distances toward and from each other, means to automatically move the elements away from each other to stretch an article engaged thereby, a manually operated charger including a gripper and edge gauge, means to cause the gripper and gauge to engage an article when the charger is moved in one direction, means for automatically releasing the article from the centralizer when the manual movement of the charger is reversed to introduce the article to the buttonhole machine, means actuated by the reverse movement of the charger to lower

the cloth clamp, and subsequently release the article from the gripper, and start the buttonhole machine.

19. In combination, a buttonhole machine comprising a cloth clamp, means for operating the cloth clamp, a centralizer for stretching and centering a collar in advance of the buttonhole machine, a manually operable charger including grippers and an edge gauge, means for disengaging the centralizer from the ends of the article being centered when moving the charger toward the buttonhole machine.

20. In combination, a buttonhole machine including a cloth clamp, means for operating the cloth clamp and starting mechanism, centralizing mechanism including two elements located in advance of the buttonhole machine, means for causing the two elements to move simultaneously toward and from each other, mechanical means for automatically operating the two elements to stretch an article to centralize it, and means for delivering the centered collar to the buttonhole machine and releasing said collar from the centralizer, operating the cloth clamp, disengaging the article from the delivery means, and starting the buttonhole machine.

21. In combination, a buttonhole machine, a centralizer comprising two pivoted moving elements of the same length, means connecting the two elements together to cause them to swing simultaneously the same distance toward and from each other, automatic means for moving the elements apart a predetermined distance, the movement apart of the two elements within the predetermined distance being limited by the article being centered, and means for delivering the centered article to the buttonhole machine.

22. In combination, a buttonhole machine, a cloth clamp, means for operating the cloth clamp, starting mechanism, a centralizer, a charger including means for gripping the centralized article, means actuated by the charger to operate the cloth clamp and release the gripping means and kick the charger from the cloth clamp, and start the buttonhole machine.

23. In combination, a buttonhole machine, a centralizer comprising a pair of pivoted arms, gears between the arms, means for causing the arms to normally spread apart, rods mounted in the arms, the ends of the rods extending beyond the arms to engage an article to be centered, means for normally projecting the rods, crank levers at the ends of the rods, a charger for delivering the centered article to the buttonhole machine, and means operated by the charger to actuate the crank levers to withdraw the rods and release the centered article.

24. In combination, a buttonhole machine, including a cloth clamp and starting mechanism, a centralizer including means to en-

gage the ends of an article to be centered, a charger, power mechanism, connecting means between the starting mechanism and cloth clamp, connecting means between the power mechanism and charger, both said connecting means being actuated when the charger is moved toward the buttonhole machine.

25. In combination, a buttonhole machine, including starting mechanism, a centralizer including devices to engage an article to be centered, a charger to introduce the centered article to the buttonhole machine, power control mechanism, connections between the power control mechanism and the charger and between the starting mechanism and the power control mechanism, said connections being controlled by the charger to operate the power control mechanism and govern the starting mechanism, and means included in the power control mechanism to disconnect the power following a predetermined actuation of such mechanism, said means permitting the power control mechanism to assume a normal position prior to the stopping of the buttonhole machine.

26. In combination, a buttonhole machine, a charger therefor, including a gripper and edge gauge, means for mounting the charger including means for moving the gripper and edge gauge toward and from the article being operated upon, power mechanism, means operated when advancing a gauged article to the buttonhole machine to operate the power mechanism to start the buttonhole machine, and means actuated by the power mechanism to raise the gripper and kick it from the buttonhole machine.

27. In combination, a buttonhole machine, a charger therefor, including a gripper and edge gauge, means for mounting the charger including means for moving the gripper and edge gauge toward and from the article being operated upon, power mechanism, means operated when advancing a gauged article to the buttonhole machine to operate the power mechanism to start the buttonhole machine, means actuated by the power mechanism to raise the gripper and kick it from the buttonhole machine, and means included in the power means for returning the means for starting the buttonhole machine and the means to raise the gripper to normal position previous to stopping the operation of the buttonhole machine.

28. In combination, a buttonhole machine, including a cloth clamp, means for gauging an article to be operated upon, a charger to deliver the article to the buttonhole machine, means for slidably mounting the charger, means for raising and lowering the charger, power mechanism, and connections between the power mechanism and the charger to lower the cloth clamp, and automatically elevate the charger from the article and kick

same away from the cloth clamp after said charger is advanced to deliver the article to the buttonhole machine, and start the buttonhole machine.

29. In combination, a buttonhole machine, a charger therefor comprising a pivoted frame, a slidable member having a recess and mounted on the pivoted frame, a post over which the member rides, the frame having a recess in alignment with the post, a rod slidably mounted in the frame, stops on the rod to cooperate with the slidable member, a gripper on the rod, power mechanism, and a connection disposed in the path of movement of one of the stops, whereby when the charger is moved in one direction one of the stops will engage the slidable member and register its recess with the post and permit the gripper to fall to engage an article and when the movement of said charger is reversed another of the stops will engage the connection and operate the power mechanism to elevate the grippers and kick said charger away from the buttonhole machine, and start the buttonhole machine.

30. In combination, a buttonhole machine, a charger including a gripper, means for permitting the charger to be raised and lowered, power mechanism, a connection between the power mechanism and the charger including means actuated by the charger for causing the power mechanism to automatically elevate the charger and kick the charger away from the buttonhole machine, and start the buttonhole machine.

31. In combination, a buttonhole machine, including starting mechanism and a cloth clamp, a charger to deliver an article to the buttonhole machine, power control mechanism including a connection to actuate the cloth clamp and the starting mechanism and a connection to the charger, power mechanism, and means operated when the connection to the charger is actuated by the latter to cause the power mechanism to operate the power control mechanism and lower the cloth clamp and automatically raise the charger and kick the latter away from the buttonhole machine, and start the buttonhole machine.

32. In combination, a buttonhole machine including a cloth clamp, starting mechanism and a latch to prevent raising the cloth clamp if the starting mechanism fails to stop in a normal position, a charger including a gripper and a gauge, power mechanism, means actuated in the movement of the charger to cause the power mechanism to lower the cloth clamp and actuate the starting mechanism and kick the charger from the buttonhole machine, and means included in the power mechanism to permit the parts to return to normal position before the buttonhole machine stops.

33. In combination, a buttonhole machine,

means for locating and introducing an article to the buttonhole machine to receive a buttonhole, a power driven element, means actuated by the collar locating and introducing means to cause the power driven element to start the buttonhole machine including means for automatically disconnecting the power driven element.

34. In combination, a buttonhole machine, a continuously driven power element, means between the buttonhole machine and power element to permit said power element to be connected and disconnected from the machine, said means including a toothed wheel normally free of the power element, and a dog to engage and operate the toothed wheel in the movement of the power element.

35. In combination, a buttonhole machine, a continuously driven power element, means between the power element and buttonhole machine to connect and disconnect said element and machine, said means including a toothed wheel normally free of the power element, and a dog for connecting said wheel to be operated by said power element, and means to return said parts to normal position, whereby the toothed wheel is free of the power element after the machine has started and prior to its stopping.

36. A collar centralizer for buttonhole stitching machines, comprising a pair of swinging arms free at their ends to engage a collar to be centered, and means connecting the arms to cause them to swing in unison in a direction away from each other to center the collar engaged.

37. A collar centralizer for buttonhole stitching machines, comprising a pair of swinging arms free at their ends to swing in an arc and to engage a collar to be centered, and means connecting the arms to cause them to swing an equal distance to and from a predetermined center, the movement of the arms from the predetermined center serving to center the collar engaged.

38. A centralizer, comprising two swinging arms, means for automatically swinging the arms from each other when centering an article, and manual means for swinging the arms toward each other.

39. A centralizer, comprising two moving elements connected together to move an equal distance toward and from each other and carrying end gauges, means to cause the two elements and gauges to move equal distances toward and from each other irrespective of the length of the article being centered, automatic means to cause the two elements to gauge and center the article, and means for holding the gauged article at its center to advance it to a machine to be operated upon.

40. A centralizer including two pivotally fulcrumed arms, the upper free ends of which are adapted to operate at equal distances from the buttonholing position of the

buttonhole machine, the ends of the said arms when in normal position being a distance apart at least equal to the over-all width of the fabric to be charged, and means to carry the centered fabric from the centralizer to a position under the clamp of the sewing machine.

41. In combination, a buttonhole machine including a cloth clamp, starting mechanism, and a latch to prevent raising the cloth clamp if the starting mechanism fails to stop in a normal position, a charger including a gripper and a gauge, a cushion, power mechanism, means actuated in the movement of the charger to cause the power mechanism to lower the cloth clamp and actuate the starting mechanism and kick the charger from the buttonhole machine and start the stitching mechanism, means included in the power mechanism to permit the parts to return to normal position before the buttonhole machine stops, and means for releasing the power means and stopping the stitching mechanism and relieving the blow through the action of the cushion when the parts are assuming a state of rest.

42. In combination, a buttonhole machine, a fabric supporting extension thereon, a charger movably supported on the machine, grippers on the charger extending over the fabric supporting extension, centering means operating to center an article relative to and on the fabric supporting extension, means to trip the grippers to cause the same to grip the article on the fabric supporting extension following the centering of the article, means to move the charger with the gripped article toward the buttonhole machine, and means for automatically releasing the article from the centering means while the charger is in operation.

43. In combination, a buttonhole machine, a fabric supporting extension thereon, a charger movably supported on the machine, grippers on the charger extending over the fabric supporting extension, centering means operating to center an article relative to and on the fabric supporting extension, means to trip the grippers to cause the same to grip the article on the fabric supporting extension following the centering of the article, means to move the charger with the gripped article toward the buttonhole machine, means for automatically releasing the article from the centering means while the charger is in operation, and means operated by the charger for automatically starting the buttonhole machine.

In testimony whereof, I affix my signature.

HENRY C. MILLER. 125
